UNITED STATES PATENT OFFICE

2,441,511

SHORT LEG FITTER

George A. Ross, Jr., Lynn, Mass.

Application November 18, 1944, Serial No. 564,153

1 Claim. (Cl. 33—3)

1

The object of my invention more particularly is to provide a simple scientific means for fitting an orthopedic shoe to the foot of a short leg, inherent since birth or as a result of the casualties of war or accident. One of the most common procedures in fitting a shoe to a foot of a short leg is to build up from a level surface to the bottom of the foot by means of books until the foot rests on the books. The height of the pile of books then measures the deficiency of the leg length, and the shoe to be made is then constructed to have enough depth of heel and sole to compensate for this deficiency in the length of the short leg thus determined. However, this is a very unscientific method and is not conducive to the best results either in efficiency of measurement for the purposes of foot hygiene or for the expeditious handling of scores of patients in a single day in some of the larger hospitals or clinics.

By means of my invention the orthopedic physician or the fitter of orthopedic shoes for a short leg is put in possession of a simple and relatively low cost scientific instrument by which he can determine by accurate measurements the data essential to shoe construction for orthopedic purposes.

In the prior art various expedients have been employed to measure wedge angles and height of ladies' high heel shoes; also for measuring the minimum height of heel with which a shoe should be equipped for the avoidance of muscle strain, etc., etc., but no device of the character of my invention has been provided which permits the necessary data to be ascertained in a few minutes with the scientific accuracy necessary to properly build an orthopedic shoe.

Another object of my invention is to provide a device for ascertaining data for orthopedic shoes which when utilized will enable the patient to apply the whole normal weight of the body on the foot as a whole and not just on the heel only, and to enable him to dorsi-flex the foot to the fullest extent without producing muscle-strain.

Still another object of my invention is to provide such adjustments that the pitch of the foot-rest of the device may be altered to permit equal weight of the body to be distributed on the ball of the foot and on the heel and to apply the data thus determined to the building of a shoe best fitted to the patient's needs.

For a more detailed understanding of my invention reference may be had to the accompanying specification and drawings in which Fig. 1 is a side elevation of my short leg fitting device; Fig. 2 is a plan view of the device shown in

2

Fig. 1; Fig. 3 is an enlarged longitudinal sectional detail showing the heel rest and adjusting means therefor taken along lines 3—3 of Fig. 2; Fig. 4 is an enlarged cross sectional view of the forepart slide and locking means therefor taken along lines 4—4 of Fig. 1 and Fig. 5 is a cross-sectional detail of the locking means for the forepart slide.

Referring more specifically to Fig. 1 it represents a platform having an inclined plane portion 2 which may be an integral part of the platform or a separate part attached thereto as by screws 3. A heel-rest 4 is adjustably supported by a member 5 and pivoted at one end to the heel-rest by a pivot 6 extending through the ears 7 of the supporting member 5. A portion 5' of the heel-rest supporting member is movable on the inclined surface 2 and retained thereon by means of a threaded clamp 8 having a nut 9 slideable in the guideway 10. A slot 11 in the platform also permits the part 5 to slide therein when it is desired to lower the level of the heel-rest 4 to the surface level of platform 1, as represented by the dotted line portion of part 5'. A thumb-nut 9' is available for loosening and tightening part 5' of the heel-rest support-member. An adjusting block 12 lies substantially at the rear end of the heel-rest and beneath the latter. To the block 12 is secured a pivotally depending stud 14 upon which is screwed a knurled adjusting nut 15. This adjusting nut 15 operates in a recess 16 which confines it so that it operates to raise or lower the block 12 by means of the stud 14 in the recess 17 thus raising or lowering member 4 by turning the knurled nut 15 in member 5. To the heel-rest 4 is pivotally attached by the hinge 16 on the pintle 17 a forefoot rest 18, the latter also having a hinge on a pintle 20. The portion of the forefoot rest between hinges 16' and 19 forms an arch support 21. The foot of the short leg to be measured is represented at 22 by the dotted lines. At the forward or toe end of the forefoot-rest 18 is a threaded nut 23 fixedly attached thereto and through which extends a threaded vertical post 24 having a flanged head 25 for turning the latter in the fixed nut 23. A slot 26 in the platform 1 permits slideable movement of the post 24 therein thus allowing the heel-rest 4 and the forefoot-rest 18 to be adjusted to correspond with the movement of the heel-rest support 5 and 5' on the inclined plane 2. Another threaded stud 27 slideable in the slot 26 at the toe end of the slot is provided with a winged clamping nut 28 for clamping against a block 29. The stud 27 is secured at its lower end to a slide 30.

The operation of my invention is as follows: The patient rests his heel on heel-rest 4, and forefoot-rest 18 is adjusted by turning flanged head 25 of upright post 24 in the fixed nut 23 until the forefoot-rest is in comfortable rest position for the forefoot; stud 27 is now slid in the slide 26 to the end of the forefoot-rest 18 and the winged nut 28 clamped to hold the stud in this position and prevent the heel-rest and forefoot-rest connected thereto from moving forward. In case any adjustment of the heel-rest is desirable this may be obtained by unloosening clamp 9 on the adjustable heel-rest support 5—5' or turning the knurled adjusting nut 15 to raise or lower heel-rest 4 about pivot 6 (in ears 7) as a radius. Loosening clamp 9 permits of moving block 5 up and down on the surface of inclined plane 2. Of course this would mean that post 24 would also have to be moved correspondingly in slide 26 and stud 27 in slide 30. Arch support 21 assumes a position of rest dependent upon the fixed position of the heel-rest and forefoot-rest.

With the human foot the elevation of the heel with respect to the toes thereof varies greatly. Therefore, the vertical distance of the lowermost point of the heel above the horizontal plane of the lowermost point in the ball of the foot is a measure of the proper arch construction of the shoe if the foot is to be maintained in its natural condition. The hinges 16' and 19 permit the arch support of the device to assume the proper position with respect to the heel-rest and forefoot-rest.

The foot of the short leg having now been properly located on the heel-rest and forefoot-rest, together with the most desirable positioning of the arch-support it is an easy matter to make measurements of the height of the heel above the floor level or level of the surface of platform 1 corresponding thereto, and likewise, also the distance and contour of the forefoot above said level. From the data thus easily ascertainable a proper shoe may be constructed for the short leg with proper contour of heel and sole.

In order to present an attractive appearance and to more properly merge the surface lines of the heel-rest and the arch-support portion of the foot-rest, a leather or other suitable cushion

member 31 may be suitably attached to the device. In accordance with the provisions of the patent statutes, I have described the principle of operation of my invention together with the apparatus which I now consider to represent the best embodiment thereof, but I desire to have it understood that the apparatus shown is only illustrative and that the invention may be carried out by other means.

10 What I claim as new and desire to secure by Letters Patent of the United States is:

A device for fitting shoes to a short leg and the like comprising a heel rest, a platform for said device having a flat and an inclined surface, means movable and securable in the inclined surface of the platform for the fitting device said means comprising a heel-rest supporting member, pivotal means carried by said last named supporting member connected to the heel-rest, means comprising an adjusting nut also carried by the last named heel-rest supporting means for adjusting the angular relation of the heel-rest, forefoot-rest, means carried by the platform for the device for adjusting the position of the forefoot-rest and means carried by the platform for securing said forefoot-rest position with respect to the plane of the heel-rest whereby substantial arch-support between the heel and the ball of the foot is obtained.
